PADDLE GAME

Joseph Di Bella, Jackson Heights, N. Y., assignor to Glassoloid Manufacturing Co., Inc., New York, N. Y., a corporation of New York

Application May 22, 1939, Serial No. 274,888

3 Claims. (Cl. 273—97)

My invention relates to a novel game paddle which has on its face a plurality of pockets adapted to receive a ball which is attached to the paddle by means of a cord.

5 My paddle is to be used for amusement purposes and comprises the apparatus necessary for playing a novel game. The paddle is approximately the size of a table tennis paddle and has attached to itself at some point a cord which at 10 its terminus carries a ball adapted to bounce upon the surface of the paddle and/or to be received by certain pockets which are formed in the paddle, said pockets carrying designated arbitrary values.

15 My invention further relates to the construction of such a paddle in which I employ a base material as the main body of the paddle and on the back thereof I place a mesh material adapted to form pockets in the manner to be described. 20 Over that mesh material I place a backing material having openings therein corresponding to the openings in the paddle itself. This backing material carries an adhesive by means of which the 25 backing itself and the mesh material are secured to the back of the paddle.

Alternatively to employing pockets beneath the openings in the paddle to receive the ball, I may use wedge shaped or tapering openings in the paddle itself, said openings being at least at one 30 end of smaller diameter than the ball, whereby the resilient ball, upon being thrown into the opening, will remain wedged therein. This construction eliminates the necessity for providing pockets beneath the openings.

35 Accordingly, it is the object of my invention to provide a novel play paddle.

It is another object of my invention to provide a novel game apparatus comprising a paddle having a multiplicity of pockets contained in the 40 face thereof, said pockets bearing markings denoting certain arbitrary values to be received when a ball attached to that paddle is successfully lodged in such pocket.

It is a further object of my invention to provide 45 a novel construction for a paddle having mesh pockets.

These and other objects of my invention will be apparent from the description which follows, taken in connection with the drawing, in which

50 Figure 1 shows a perspective view of the paddle of my invention in which I show the position of the ball carried by the string, both in the dropped position and also in a position in which the ball is lodged in one of the pockets carried by the paddle.

Figure 2 is a cross-section taken along the line 2—2 of Figure 1.

Figure 3 is a cross-sectional view showing the construction and the method of construction of the paddle of my invention.

Figure 4 is a side elevation of a modified form of my invention.

Referring now more specifically to Figure 1, I show a paddle 1 which is of the general size of a table tennis paddle or a ball mounting paddle 10 such as are known in the art. The paddle has a suitable handle 2 which widens at its end 3. Attached to the paddle 1 by the fastening means 4 is a cord 5 which carries a ball 6 which may be of rubber or any suitable resilient material. The 15 cord 5 may be ordinary cord or string material or may possibly be of rubber.

The ball is shown at 6' in its normally depended position. On the face of the paddle 1 are openings 7 therein in which are mesh pockets 8. 20 On the face of the paddle and adjacent each pocket is an arbitrary numerical value such as 5, 10 or 15, indicated by the numeral 10.

Referring now more specifically to Figure 2, which is a cross-section of Figure 1, it is to be 25 noted that the main body of the paddle 1 may be formed of laminated ply wood 11. It can also be here seen that the pockets 8 are formed of a continuous mesh material 12 which extends over the back of the paddle and is secured to the paddle 30 by the backing 13 which may be of cardboard or any suitable stiff material.

The paddle can be of any suitable material, such as wood, plastic or metal.

In Figure 3 I show the method of construction 35 of my paddle. There I show a table member 15 on which is placed the plywood paddle body 11 having the openings 7 therein. Through this opening 7 projects a shaping member or jig 16 over which is disposed the mesh material which 40 is fabric 12 so that the jig forms a pocket of the desired size in the proper position. Thereafter the stiff backing member 13 is coated with an adhesive such as a suitable glue and applied over the fabric whereupon the assembly is pressed 45 to cause a firm adhesion between the respective parts. The adhesive on the backing member 13 naturally strikes through the mesh fabric and secures both the backing material and the mesh fabric firmly to the back of the plywood material 50 which is the main body of the paddle.

By means of this assembly I can rapidly and efficiently form a paddle with mesh pockets which are of unusual strength. That is, because the mesh extends entirely over the back of 55

the paddle, there can be no partial separation of or pulling out of the mesh at any individual pocket.

The backing that secures the pocket material 5 to the paddle may be in the form of individual rings which secure the pocket material to the paddle immediately adjacent the holes.

Preformed cups having flanges which may be inserted from the top of the paddle with the 10 flanges on the upper surface of the paddle may be used, or such flanged cups may be attached to the back of the paddle, in which case the securing means attach the cups through the flanges.

15 Referring now to Figure 4 in which I show a modified form of my invention, I show in side elevation the paddle 20 which carries the pockets 21 and 22 and the depending ball 23 which is attached to the paddle at 24 by the cord 25. As 20 shown above, the pockets 21 and 22 are formed integral with a mesh material 26 which extends across the back of the paddle. The mesh material is secured to the back of the paddle by the backing material 27. The feature of this modification is the facing material 30 which lies on 25 top of the paddle and which may be of a soft material such as a felt or flocculent cardboard. This soft facing material is for the purpose of dampening the bouncing action of the ball on the 30 face of the paddle in order to allow the user to more easily guide the ball into a desired pocket. This facing material may be a rough flocculent material as has been pointed out or it may be of corrugated material in order to render more 35 haphazard the action of the ball.

As a further modification I may provide a ridge or guard rail running around the edge of the paddle to prevent the ball from rolling off the face of the paddle, but it is to be understood 40 that this is a modification which may or may not be employed.

The pocket material, in lieu of mesh fabric, may be of plastic material, such as sheetings or paper, etc. Crossed wires may also be used as 45 pockets.

The use of the paddle of my invention is as follows:

The ball 6 carried on the end of the cord 5 is thrown into the air in any desired manner, as 50 by rapid movement of the paddle itself, and upon the ball descending the paddle is rapidly moved so that the ball is received in one of the respective pockets in the face of the paddle. The pockets are relatively deep so that the ball can 55 be securely received therein. However, since the pockets are of a diameter only slightly larger than the diameter of the ball itself, it is rather difficult to place the ball in one of the pockets without exercise of skill. The resilience of the ball and its consequent bouncing on the face of the paddle render the game more difficult and amusing.

The cord which holds the ball may be attached to the paddle at any desired point and the point 5 illustrated in the drawings is merely one of a number of desirable locations therefor. Because of the different markings on the respective pockets of the paddle, there are advantages gained by accurate placement of the ball in any particular pocket. That is, the quickness of the eye and facility of handling which are requisite to this game are enhanced by the resultant increased values for placement of the ball in a particular pocket. 10

One of the holes, for example the top hole, may provide a premium in the form of a doubled score for all points previously made, and this 15 premium hole is made smaller in diameter to make it more difficult to place the ball therein.

When the modified form of my invention is employed in which the paddle is faced with a soft material which does not cause the ball to 20 bounce as much as the plywood shown in the form of Figure 1 of the drawing, the game is played with more ease, but at the same time skill and quickness of handling are necessary to obtain good competitive scores. 25

The specific forms shown and described are given by way of example and it is to be understood that the paddle may be modified by varying the number of pockets and their position as well as varying the position of the cord which 30 carries the ball.

Further, although the manner of construction of the paddle is of particular value, I do not intend to limit my invention to that particular construction, but only with respect to the scope 35 of the appended claims.

I claim:

1. A game paddle comprising a body and a handle, said body having a plurality of openings 40 therein, a layer of mesh material extending over the back of said paddle, said mesh material being formed into pockets beneath said openings, and a ball tethered to said paddle.

2. A game paddle comprising a body and a handle, said body having a plurality of openings 45 therein, a layer of mesh material extending over the back of said paddle, said mesh material being formed into pockets beneath said openings, and a backing material securing said mesh to said paddle, and a ball tethered to said paddle. 50

3. The method of manufacturing a game paddle having pockets therein which comprises forming an opening in said paddle, projecting a jig through said opening in said paddle, placing a layer of flexible material over the back of said paddle and over said projecting jig whereby the projecting jig forms a pocket in the flexible material, and applying a backing material over said flexible material to secure said flexible material to the back of said paddle. 55

JOSEPH DI BELLA.
